UNITED STATES PATENT OFFICE.

PAUL LEON GEORGES KREUTZBERGER AND PIERRE GERMAIN, OF BELLEVUE-MEUDON, FRANCE.

PROCESS AND APPARATUS FOR BURNING HEAVY HYDROCARBONS.

Application filed January 26, 1922. Serial No. 531,933.

To all whom it may concern:

Be it known that we, PAUL LEON GEORGES KREUTZBERGER, engineer, residing at 8 rue des Buttes, Bellevue-Meudon, Seine and Oise, France, and PIERRE GERMAIN, engineer, residing at 29 Grande Rue, Bellevue-Meudon, Seine and Oise, France, have invented new and useful Improvements in Processes and Apparatus for Burning Heavy Hydrocarbons, of which the following is a specification.

The present invention relates to improvements in apparatus for burning heavy hydrocarbons.

15 The method of operation, which is utilizable in large industrial plants, becomes impossible for household purposes or, generally speaking, those which do not feed steam boilers.

20 The process described below is intended for use with this latter class of apparatus, which in principle is akin to that used in smoke-consuming furnaces in which the complete combustion can be obtained even 25 of very heavy fuels which would produce in ordinary furnaces, and especially after each change, a thick tarry smoke. With this end in view combustion is effected in two stages; in the first stage it has a reducing effect, as in a gas producer, and in the second, the products of distillation, the smoke and the oxide of carbon resulting 30 from the effects of the first stage, are re-ignited by means of a certain quantity of supplementary air which is more or less 35 heated and supplied slightly in excess for the purpose of ensuring the complete oxidation of all the products.

40 The simplest type of these furnaces can be constituted by merely admitting a suitable quantity of air above the grate of an ordinary furnace in addition to that drawn in the ash pan.

45 A large number of devices of this kind have been constructed and, in the case of automatic feed stokers the method of operation is extremely simple, the proportion of oxide of carbon and the products of distillation of the coal remain substantially 50 constant for a predetermined rate of combustion which permits of using the air inlet openings placed below and above the grate; the regulation of these openings is not necessary except in cases where such rate is 55 varied.

If the case is considered of an apparatus designed to burn a liquid at a constant rate, which liquid flows in a uniform manner through a suitably arranged regulating cock, the conditions are similar to the furnace cited above, having a continuous feed.

Under these conditions, Fig. 1 annexed to the present application by way of example shows a longitudinal section of the apparatus as a whole. Fig. 2 represents an elevation of the portion of Figure 1 situated immediately above the body of the stove. Fig. 3 is a vertical section along line A, B, C, D of the former figure. Fig. 4 is a section along the line E, F. of Fig. 2 and Fig. 5 is a section along the line G, K. of Fig. 2.

In Figs. 1 and 4 *a* represents the fuel reservoir and *b* a waterbath for the purpose of heating *a* so as to render the liquid fuel 75 suitably fluid. The water-bath is fed by the small constant level reservoir *c* and heated by the gases of combustion passing through the chimney *d*. A Mariotte tube *e* immersed in the reservoir *a* insures a constant 80 supply of thinned out liquid on condition that the lid *f* is tight, whatever may be its level in the reservoir *a*.

It would also be possible to use for this purpose, at the exit from *a*, a reservoir having a constant level such as *c*.

A needle valve surrounded by an insulating substance and operated by the worm-wheel *h* and the worm *i*, *i'* which is fixed to the screw *j*, which by the intermediary 90 of the nut *k*, in contact with the fixed tongue *l* of the link *m* and of the collar *n* carrying four obturators *o*¹, *o*², *o*³, *o*⁴, permits of obturating to a greater or less extent the tubes *p*¹, *p*², *p*³, *p*⁴ which enter the body of the 95 stove *q*, which is protected by a refractory casing *q*¹ and a second casing *q*². These tubes have their lower portion curved upwardly so as to penetrate into the twyer *r* which is constricted at *r*¹ and then widens 100 out so as to connect with the chimney at *r*².

The needle valve *g* described above delivers the liquid by a pipe *g*¹ which opens in the interior of the stove just above the first spiral of the coil *s*, the section of which has 105 a semicircular shape forming a channel.

The last spiral of the said coil terminates above the nickel-steel basket *t* provided with asbestos wicks. The lower portion of the stove is closed by a tight box *u* through 110

which pass the three air conduits v^1 , v^2 , v^3 which can be closed in the same way as the orifices x^1 , x^2 , x^3 , x^4 of the upper portion of the stove. The conduits v^1 and v^2 terminate under the grate y which serves for ignition.

The method of operation of the apparatus of which the different parts have just been described is the following.

By means of the combustion of chips of wood, twigs and the like, more or less moistened with petroleum and preliminarily placed on the grate y a temperature is produced in the twyer r which is sufficiently high to cause ignition of the vapours of mazout. The constricted portion r^1 of the twyer being of considerable thickness, retains a large proportion of the heat. The cock g is then gradually opened and the mazout, being thus released, flows as has already been described into the helicoidal channel. In order to ensure sufficient fluidity of the mazout at the beginning one places boiling water in the water-bath b .

The mazout slowly descending the incline 25 of the channel, which is slight, in a heated space, is transformed into vapour which is incompletely oxidized by the air sucked in through the apertures x^1 , x^2 , x^3 , x^4 . The smoke produced in this way and the excess of vapours arrive by aspiration into the superheated zone r^1 where the supplementary air feed through the heated pipes p^1 , p^2 , p^3 , p^4 enables their complete combustion to be effected. The regulation of this 30 quantity of air is obtained simultaneously with that of the flow of liquid fuel by the mechanism placed in the open air between the upper portion of the stove and the water-bath of the mazout reservoir. The 35 knurled wheel i^1 actuates on the one hand the cock g by means of the wheel h and wormwheel i and on the other hand the obturators o^1 , o^2 , o^3 , o^4 by the nut k mounted on the screw j which drives, by means of the link m , the collar n fixed to the above 40 mentioned obturators. The regulation of the relation of these two operations should take account of the pitch of the screw-threads, lever arms, etc. as well as of the 45 constant supply of liquid above the needle valve, which supply plays a favourable part in cases where the flow of the liquid takes place according to a law more or less approximate to that of Poisouille.

Under these circumstances it is possible to obtain a constant proportion between the flow of air and liquid for all rates of combustion.

In cases where at the beginning of the operation, a small quantity of mazout might happen not to be burnt, the residue would flow into the nickel-steel wire basket t fitted with asbestos wicks which, being raised to a high temperature, would complete its combustion.

Nevertheless, in case of accidental extinction, the liquid would flow into the tight box u which should have a sufficient volume to receive the reserve quantity in the reservoir a . The curved form of the tubes v^2 , v^3 ensures tightness of the box while at the same time permitting at the moment of ignition, the addition of air under the grate y .

We claim:

1. An apparatus for burning heavy hydrocarbons, comprising means for preliminarily heating said hydro-carbon, means for feeding air thereto to effect partial combustion, a central twyer, means for feeding the products of said partial combustion to said twyer, and means for feeding additional air to said twyer to effect complete combustion. 75

2. An apparatus for burning heavy hydrocarbons, comprising means for preliminarily heating said hydro-carbon, means for feeding air thereto to effect partial combustion, a central twyer having a contracted portion, means for feeding the products of partial combustion to said twyer, and means for feeding additional air to said twyer to effect complete combustion. 85

3. An apparatus for burning heavy hydrocarbons, comprising means for preliminarily heating said hydro-carbon, means for feeding air thereto to effect partial combustion, a central twyer having a contracted portion of increased thickness, means for feeding the products of partial combustion to said twyer and means for feeding additional air to said twyer to effect complete combustion. 95

4. An apparatus for burning heavy hydrocarbons, comprising a casing, a central twyer in said casing, a spiral channel surrounding said twyer, means for feeding fuel to said channel, means for heating said channel, means for supplying air to the fuel in said channel sufficient for effecting partial combustion of said fuel, and air-conduits passing through said casing and opening into said twyer, for the purpose of drawing the products of partial combustion into said twyer. 105

5. An apparatus for burning heavy hydrocarbons, comprising a casing, a central twyer in said casing and communicating at its lower end with the interior of said casing, an open spiral channel surrounding said twyer, means for feeding fuel to said channel, means for heating said channel, means for supplying air to the fuel in said channel for effecting partial combustion of said fuel, and air-conduits passing through said casing and opening into said twyer to effect complete combustion of the fuel. 115

6. An apparatus for burning heavy hydrocarbons, comprising a fuel reservoir, a relatively large surface, means for feeding fuel to said surface, means for heating said surface, means for feeding air to said surface to cause partial combustion of the fuel, means for drawing off the products of said 125

130

partial combustion, a second air-supplying means for completing the combustion and means for simultaneously regulating the feed of air and fuel.

5 7. An apparatus for burning heavy hydrocarbons, comprising a relatively large surface, means for feeding fuel to said surface, means for heating said surface, means for feeding air to said surface to cause partial combustion of the fuel, means for drawing off the products of said partial combustion, a second air-supplying means for completing the combustion, a valve for controlling the supply of fuel, means for controlling the supply of air and means for adjusting said valve and air-supplying means simultaneously.

8. An apparatus for burning heavy hydrocarbons, comprising an outer casing, a helicoidal channel of slight inclination but of large surface within said casing, means for feeding fuel to said channel, a converging-diverging twyer in said casing and surrounded by said channel, the contracted por-

tion of said twyer being of increased thickness so as to form a heat-reservoir, two sets of orifices for the admission of air, one of said sets being adapted to conduct the air to the said contracted portion of the twyer and means for regulating the feed of fuel in proportion to the air drawn in by the draft.

9. An apparatus for burning heavy hydrocarbons, comprising a casing, a central twyer in said casing, a helicoidal open channel of small incline but large surface surrounding said twyer, means for heating said channel, means for supplying air to said channel to effect partial combustion of the fuel, means for drawing off the products of partial combustion to the mouth of said twyer, means for supplying air to said twyer to effect complete combustion, a wire basket having asbestos wicks located below said twyer or adapted to catch any unburnt fuel and a grate beneath said basket for the purpose of starting the operation of the apparatus.

PAUL LEON GEORGES KREUTZBERGER.

PIERRE GERMAIN.
